METHOD AND APPARATUS FOR BROADCASTING AND RECEIVING RADIO SIGNALS

Filed Aug. 24, 1926

UNITED STATES PATENT OFFICE

HENRY C. DE VORE, OF MONONGAHELA, PENNSYLVANIA, ASSIGNOR TO HENRY B. DE VORE, OF WILMINGTON, DELAWARE

METHOD AND APPARATUS FOR BROADCASTING AND RECEIVING RADIO SIGNALS

Application filed August 24, 1926. Serial No. 131,182.

This invention relates to the transmission of signals by radio and is particularly adapted to radio telephony.

In the broadcasting of programs by radio considerable difficulty is encountered in providing for a sufficient number of stations in the permissive band of wave lengths. The range of wave lengths between which broadcasting stations can operate is necessarily restricted, and if there is to be no overlapping, each station must have a wave length different from every other station, and the degree of separation in the wave lengths between stations must be appreciable. This necessarily means that only a very definite number of stations can operate at the same time. The number of stations which can operate at the same time is far below the number of stations that actually exist, and a very considerable difficulty is encountered in providing for the establishment of new stations. This is imposing a considerable restriction and limitation in the use of radio.

The present invention has for its primary object to provide a system whereby the range of broadcasting can be increased between the maximum and minimum limits now provided so that more stations can broadcast without interfering with one another.

The invention contemplates primarily that the broadcasting station shall simultaneously transmit its program on two or more wave lengths. With different combinations of two or more wave lengths the mathematical progression is such that several thousand broadcasting stations could operate without interference, where, at the present time, the range permits of only a few hundred broadcasting stations.

That two stations can broadcast the same program simultaneously on two or more wave lengths is well known, and is at the present time practiced. It is also well known that several stations may simultaneously broadcast the same program on different wave lengths, and the present invention is also applicable to such a system of broadcasting.

According to the present invention it is proposed to provide means at the receiving end of the circuit which would respond to its

maximum when it is receiving selected program on the two or more wave lengths on which the program is being broadcast, but which will select out and bypass all other signals which are being broadcast on any one of the wave lengths common to those being received.

For example, the invention proposes that one station may operate on 200 and 225 meter wave lengths, another station on 200 and 250 meter wave lengths, another station on 200 and 275 meter wave lengths, and so on until the upper wave limit is reached. Another series of stations would operate with combinations of 225 meter wave lengths and another wave length, as for instance 225 meters and 250 meters. Other series of stations would operate on other combinations of wave lengths in the same way. With the present invention, assuming it was desired to tune in on that station broadcasting on 200 and 225 meter wave lengths, none of the other stations having a 200 meter wave length as one of its wave lengths or having a 225 meter wave length as one of its wave lengths would interfere with the program being received.

Another example of the use of my invention is the simultaneous reception of two or more stations broadcasting the same program simultaneously on different wave lengths. Signals (other than those desired) which may be broadcast on any of the wave lengths common to those being received are selected out, so that only the desired signals pass through the receiver to the translating device used.

The invention may be more readily understood by reference to the accompanying drawing which illustrates diagrammatically a receiving circuit embodying my invention.

At the receiving station there are two independent receiving sets, one of which is designated "A" and the other of which is designated "B". These receiving sets may be of any known or preferred type, and in the drawing they have been only schematically illustrated. Each receiving set has a rectifier therein, 2 designating the rectifier of the set "A" and 3 designating the rectifier of the set "B". These rectifiers are indicated as

being preferably, but not necessarily, of the thermionic type. In the illustrated example each rectifier has an anode which is in circuit with a source of direct current, these sources 5 of direct current being designated 4 and 5 respectively. In series with the anode of the rectifier 2 are two coils 6 and 7. Coil 6 is inductively disposed with respect to a coil 8 and coil 7 is inductively disposed with respect 10 to coil 9. The direction of a current flow in coils 6 and 7 is preferably the same.

The output or anode of the rectifier 3 is in series with a coil 10, also inductively disposed with respect to coil 8 and coil 11, which is also 15 inductively disposed to coil 9. The coils 6 and 10 are of the same value, and the coils 7 and 11 are of the same value, but the direction of current flow through the coil 10 is reversed with respect to the current flow 20 through the coil 6. The direction of current flow in the coil 11 is the same as the direction of current flow in the coil 7. As thus arranged the fields of coils 6 and 10 tend to neutralize each other so as to induce no current through the coil 8, while the effect of the coils 7 and 11 is to work together to induce a current flow in the coil 9.

While the electrical characteristics of coils 8 and 9 are not necessarily the same as the 30 electrical characteristics of coils 6, 7, 10 and 11, the various coils are preferably of such value and are so disposed that, for a given voltage value and frequency, the inductive effect of coil 6 or 10 on coil 8 will be the same 35 as the inductive effect of coil 7 or 11 on coil 9.

The opposite ends of the coil 8 are connected with the control electrodes or grids of the electron relays 12 and 13 respectively. The output sides of anodes of these relays 12 40 and 13 are connected together and are in series with a source plate voltage 14. Included in the output circuit of the relays 12 and 13 is a coil 15, whose other side is connected to the cathode terminals of the respective relays 12 and 13.

The coil 9 is similarly coupled with a coil 16 through thermionic relays 17 and 18. At 45 is indicated the source of plate voltage for the electron relays 17 and 18. The coils 15 and 16 are inductively disposed with respect to a coil 20, but the direction of current flow through the coil 15 is reversed with respect to the direction of current flow 50 through the coil 16, so that the magnetic fields of the two tend to neutralize each other in their inductive effect on the coil 20. The coil 20 may be in circuit with a telephone or other translating device, either directly or 55 through any suitable audio-frequency amplifying circuit such as that indicated diagrammatically at 21. The telephone or translating device is designated 22. For the purpose of simplification the audio-frequency amplifier means 21 is only schematic-

ally indicated, as this in itself forms no part of the present invention and is now well understood by those skilled in the art.

The operation of the circuit may now be traced. Assume that a station to be received 70 is broadcasting both on 200 meter wave lengths and 225 meter wave lengths. Set "A" is tuned to receive the signals at 200 meters and set "B" is tuned to receive the signals at 225 meters. Flowing through the coils 6 and 7 is an undulatory direct current whose undulations correspond to the received signal impulses, and flowing through the coils 10 and 11 is a similar undulatory direct current. 75

Coils 7 and 11 will act in conjunction to 80 induce a current flow through the coil 9. This current flow through the coil 9 will correspondingly modulate a current flow through the coil 16 and the coil 16 will induce a corresponding current in coil 20 which will be 85 made audible in the translating device 22.

It will be apparent that the same action 90 takes place when the different wave lengths are received from different stations, the same signals, of course, being broadcast simultaneously on the different wave lengths.

Now assume that set "A", in addition to receiving the station which it is desired to receive, is also receiving a second station which also has a 200 meter wave length as one 95 of its broadcasting wave lengths. Set "A" will necessarily respond to this second station as well as to the first. This will mean that in addition to the signals which it is desired to receive, there will be other undulations in the 100 current in the coils 6 and 7. These other undulations will not be correspondingly set up in the coils 10 and 11 because set "B" is tuned to respond to 225 meters.

The disturbing undulations passing through the coil 8 will not 105 be neutralized by the field of the coil 10 so that a current will be induced in the coil 8 corresponding to the undesired undulations passing through the coil 6. The undesired undulations of the second station will also 110 inductively effect coil 9, so that a current will flow through coil 16 which undulates both in accordance with the desired station and the undesired station. The currents induced in coil 8, corresponding only to the undesired 115 undulations of set "A", will cause a correspondingly undulating current to flow through coil 15. Coils 15 and 16 act in opposition, so that there will be induced in coil 20 a current flow corresponding only to the 120 desired undulations of the first station, while the undesired undulations of the second station will be balanced out, and the telephone 22 will be actuated only in accordance with the signals which both sets "A" and "B" are 125 simultaneously receiving.

In the same way, any signals which are disturbing to set "B" that are not received in set "A" will be correspondingly neutralized.

If the signals received on one wave length 130

are stronger than the same signals on other wave lengths, the excess strength over the weaker signal will be neutralized in the receiver, and the signals in coil 20 will (when using two sets such as "A" and "B") be twice the strength of the weaker signal in the coil 20. This is apparent from the diagram and what has been said above.

It will be understood that the relays 12 and 13, and 17 and 18, are not necessarily of the type illustrated, since any desired device may be used which produces a flow in coil 15 or 16 proportional to the flow in coil 8 or 9, it being desirable, of course, to avoid distortion. If thermionic tubes are used, as illustrated, care should be taken that they are operated on the proper portion of their characteristic curves so that an increase in current flow in one will be substantially compensated for by a corresponding decrease in current flow of the other to avoid distortion.

The advantages of the invention arise from the fact that the number of broadcasting stations which can operate within a given range can be very effectively increased without one station interfering with another. It will be seen that the only time that there can be any interference would be when two stations having one of their two wave lengths common would broadcast the same note at exactly the same time, in which case there might be some increase noticeable in the output of the telephone, but these occasions would necessarily be rare, and if, instead of having but two sets "A" and "B" there were three or more sets, the chance of this happening could be even more effectively reduced. Not only will the present system tend to eliminate interference with other stations, but will tend to reduce the interference produced by local and other disturbances, to some extent. For instance, the antennas for the two stations could be at right angles or widely separated so that they would not respond to the same extent to static or other disturbances, and a more quiet reception could be secured.

While it is realized that it might, for some time, be impractical to immediately have all broadcasting stations transmit on two wave lengths, it is possible that a certain section in the available bands of wave lengths could be allotted to stations desiring to use the present method. This could be done without injury to the present system and without rendering all present receiving equipment obsolete. As a matter of fact the arrangement indicated in the drawing could be assembled in a case with jacks for plugging into the detector or audio-frequency output of sets of the present type.

It will be apparent that the diagrammatic illustration does not define the limits of my invention, but that the coils may be variously disposed and the circuits altered to carry out

the principles involved and obtain the advantageous results.

While I have described and illustrated one proposed embodiment of my invention, it will be understood that the invention is not restricted to use with only two receiving sets, as the invention is applicable to the arrangement wherein a station could broadcast on three or four or more wave lengths, and various changes and modifications may be made in the invention within the contemplation thereof and under the scope of the following claims.

I claim:

1. The method of radio-signaling which consists in transmitting a continuous wave signal simultaneously on a plurality of wave lengths, separately receiving and rectifying the signals, impressing the rectified audio-frequency currents on a common translating device, and balancing out audio-frequency currents not common to all of the signals being separately received.

2. A system for receiving and translating radio signals which are simultaneously broadcast on a plurality of different wave lengths while neutralizing any signals not common to all of the wave lengths being received including means for rectifying received signal impulses on separate wave lengths, a circuit responsive to all impulses which are rectified, a circuit responsive only to signals which are not common to all of the wave lengths being received, said circuits being oppositely coupled to a translating circuit whereby signal impulses in the second circuit are neutralized by the corresponding impulses in the first circuit.

3. A system for the reception of the same radio signals simultaneously transmitted on a plurality of wave lengths without interference, including a separate receiving circuit for each wave length on which the signal is broadcast, each receiving circuit having its output inductively impressed on two local circuits, one of which responds to all of the impulses in the several output circuits and the other of which responds to only those impulses which are not common to all of the output circuits of the several receiving circuits, and a translating circuit to which the two local circuits are inductively coupled in reverse phase relation whereby like current values in the two circuits are neutralized by each other and the translating circuit caused to respond to the difference.

4. A system for the reception of the same radio signals simultaneously transmitted on a plurality of wave lengths without interference which consists in a receiving circuit having a receiving set for each wave length on which the signal is broadcast, each receiving set having an audio-frequency output, a local circuit into which the audio-frequency impulses of the several stations is impressed,

3 a second local circuit which responds only to those audio-frequency currents in the several receiving circuits which are not common to all of the receiving circuits, said local circuits being inductively coupled in reverse phase relation to a translating circuit whereby like current impulses in the two local circuits are neutralized and the translating circuit caused to respond to the difference in the 10 current values in the two circuits only.

5. A system for the reception of the same radio signals simultaneously transmitted on at least two wave lengths, including at least 15 two separate receiving circuits, each having a rectifier, one receiver having its rectifier output passed through two coils wound in the same direction, the other receiving circuit having its rectified output passed through two other coils, one of which is wound 20 reversely to one of the coils of the first circuit and one of which is wound the same as the coils of the first circuit, a coil inductively interposed in the fields of the oppositely wound coils of the respective receiving 25 circuits, a second coil inductively interposed between the like coils of the respective receiving circuits, a translating circuit, and means for inductively impressing current impulses induced in said first and second coils 30 in reverse phase relation on the translating circuit, current impulses of like value induced in the first and second coils thereby being neutralized and the translating circuit caused to respond only to current impulses which are 35 different from those induced in the first coil only.

6. A system for the reception of the same radio signals simultaneously transmitted on at least two wave lengths, including at least 40 two separate receiving circuits, each having a rectifier, one receiver having its rectifier output passed through two coils wound in the same direction, the other receiving circuit having its rectified output passed through 45 two other coils, one of which is wound reversely to one of the coils of the first circuit and one of which is wound the same as the coils of the first circuit, a coil inductively interposed in the fields of the oppositely wound coils of the respective receiving 50 circuits, a second coil inductively interposed between the like coils of the respective receiving circuits, an electron relay circuit connected across the terminals of the first coil, a second electron relay circuit connected across the terminals of the second coil, a separate coil in the output sides of the electron relay circuits for said first and second coils, said last named coils being effectively reversed, 55 whereby their fields tend to oppose each other, another coil inductively disposed with relation to said last named coils, and a translating device responsive to current impulses induced in said last named coil.

60 7. A system for the reception of the same

radio signals simultaneously transmitted on at least two wave lengths, including at least 70 two separate receiving circuits, each having a rectifier, one receiver having its rectifier output passed through two coils wound in the same direction, the other receiving circuit having its rectified output passed through two other coils, one of which is wound reversely to one of the coils of the first circuit and one of which is wound the same as the 75 coils of the first circuit, a coil inductively interposed in the fields of the oppositely wound coils of the respective receiving circuits, a second coil inductively interposed between the like coils of the respective receiving circuits, a translating circuit, an electron relay circuit for each of said first and second coils, the output of said electron relay circuits being inductively coupled in reverse phase relation to the translating circuit.

80 In testimony whereof I have hereunto set my hand.
